ATTORNEY

UNITED STATES PATENT OFFICE.

NORRIS ELMORE CLARK, OF PLAINVILLE, CONNECTICUT.

METAL FABRIC.

1,104,475.

Specification of Letters Patent. Patented July 21, 1914.

Application filed October 15, 1909. Serial No. 522,734.

To all whom it may concern:

Be it known that I, NORRIS ELMORE CLARK, a citizen of the United States, residing at Plainville, in the county of Hartford and State of Connecticut, have invented certain new and useful Improvements in Metal Fabrics, of which the following is a specification.

My invention relates particularly to what 10 is termed expanded metal.

The principal objects are to give greater 15 rigidity to the product, increase its holding power and value for such uses as plaster and concrete work and facilitate its manufacture.

My Patent #930,350 dated August 10th, 1909, shows a fabric of the general character to which the present invention relates. Such a fabric has, integral with the reticulated portions, one or more strips usually 20 running lengthwise of the sheet which constitute tension members and which for convenience I will term "rods" although I do not wish to be limited by use of that term 25 to any particular cross sectional shape of strip. Often the fabric has three or more of these rods alternating with the expanded portions and usually a rod on each edge or margin of the sheet.

30 The particular point to this invention lies in the corrugation or crimping of these rods in a direction transverse or cross-wise of their lengths so as to stiffen the rods, avoid broad flat surfaces and prevent buckling and 35 irregularity in making.

Figure 1, shows a plan view of a fragment of fabric embodying my invention. Fig. 2, is an end view thereof. Fig. 3, is an edge view showing the corrugated side rod. Fig. 40 4, is a transverse section of a fabric of my invention with the side rods turned edge-wise to the plane of the fabric. Fig. 5, is a detail transverse section showing an intermediate rod turned edge-wise to the plane of 45 the fabric. Fig. 6, is a detail transverse section showing a rod formed of a flat strip bent into a channel-like form.

The fabric shown in Fig. 1 has rods 1, 2 and 3 with intermediate expanded portions 50 4 and 5. Each expanded portion in the particular form shown is composed of a series of zig-zag bent strands such as 6, 7 and 8 which integrally connect the adjacent rods such as 1 and 2. Adjacent strands are integrally 55 connected together preferably at a

plurality of points such as 9 and 10 and arranged on edge. In Figs. 1, 2 and 3 all the rods 1, 2 and 3 lie generally in the plane of the fabric.

The rods are crimped or corrugated transversely as at 11 and 12. The corrugations need not be the same size and shape in the different rods. For instance the corrugations 11 in the marginal or side rods such as 1 may be small and close together while the 60 corrugations 12 in the interior rods such as 2 and 3 may be farther apart. The corrugations 12, 12 I have shown as at or near the point of junction of the strands 6, 7, etc., with the rod 2. This location permits 65 the strands to be bent easier and with less danger of fracture.

The fabric of Fig. 4 has the side rods 13 and 14 turned edgewise and the intermediate or interior rods 15, 16 and 17 in the general 70 plane of the fabric.

In Fig. 5, I have shown an intermediate rod 18 turned on edge.

In Fig. 6, I have shown a channel-like 80 rod 19. These are simply to illustrate some of the different kinds of rods which may be employed in fabrics of my invention. They are all adapted to form longitudinal tension members, or beams in concrete, cement, and plaster work. Different forms will be used 85 depending upon the use to which it is to be put or the method of manufacture or the weight of fabric desired.

The transverse corrugations stiffen the rods and increase the holding power in 90 plaster and concrete work. They also avoid the formation of lines of cleavage which are likely to occur when the rods have broad, flat or unbroken surfaces. Expanded metal is usually formed by slitting or cutting 95 stock so as to form strands connected in staggered arrangement. These strands are bent either in the operation of slitting or in separate bending or stretching operations. In forming expanded fabrics of the character herein set forth there is a tendency for the rods to buckle when the expanded portions are being formed because the slitted section is somewhat foreshortened in expanding laterally. The amount of fore- 100 shortening depends upon the angle which the slits make relative to the axes of the rods and also upon the method of expansion and the character of mechanism employed. By giving uniform transverse corrugations 110

to the ribs the foreshortening of the slitted section is compensated for and buckling is avoided.

The angle which the corrugations make relative to the longitudinal axes of the rods may be varied within considerably wide limits and the degree or extent of corrugation may be varied according to the necessities of the case as determined for instance by the character and thickness of metal, the angle of slitting, the method and degree of expansion and the mechanism employed. I wish it understood that so far as the broader claims are concerned I do not consider the invention as limited to the particular design, arrangement and details illustrated herein.

It is preferred to have the strands arranged on edge and to have the general direction of the strands in adjacent expanded portions inclined in opposite directions relative to the longitudinal axes of the rods. This affords shelves or keys in all directions so that plaster can be applied more readily and will adhere. When the rods lie generally in the plane of the fabric the transverse corrugations increase the effective thickness of the rods so that the fabric is of more nearly a uniform thickness throughout.

What I claim is:—

1. The improved expanded metal having one or more sections thereof in the form of expanded meshes, and one or more non-expanded sections integral with the first and made with shortenings by which its length is equalized with that of the expanded section.

2. The improved expanded metal having one or more sections thereof in the form of expanded meshes, and one or more non-expanded sections integral with the expanded section and corrugated at an angle to the length thereof whereby such length is equalized with that of the expanded section.

3. The improved sheet metal formed into a series of sections, alternately expanded and non-expanded, the non-expanded sec-

tions ribbed and having shortenings by which their length is equalized with that of the expanded sections.

4. The improved sheet metal formed into a series of sections, alternately expanded and non-expanded, the non-expanded sections ribbed and being corrugated transversely of the length thereof whereby such length is reduced.

5. An expanded metal fabric comprising parallel rods of entire metal corrugated at intervals transversely throughout their lengths and expanded portions integrally connecting said rods.

6. An expanded metal fabric comprising a plurality of longitudinal rods of entire metal corrugated transversely of their lengths and an expanded portion integrally connecting each two adjacent rods.

7. An expanded metal fabric comprising parallel rods of entire metal corrugated transversely, and a series of zigzag bent strands integrally connecting adjacent rods, the strands of adjacent sections being oppositely inclined, the corrugations of some of the rods being at the points of connection of the strands.

8. An expanded metal fabric consisting of parallel marginal strips of entire metal and integrally connecting expanded sections, the marginal strips being corrugated transversely to their length.

9. A reinforcing material for cement and concrete work consisting of longitudinal strips of entire metal corrugated transversely of their lengths and providing alternating transverse shoulders and recesses on opposite sides and a reticulated section integral with said entire metal strips and consisting of a plurality of rows of narrow strands with small openings between the strands arranged in a plurality of rows.

NORRIS ELMORE CLARK.
